UNITED STATES PATENT OFFICE.

MATTHEW J. CARBONI, OF NEW YORK, N. Y.

ELECTRIC SIGN.

1,393,008.

Specification of Letters Patent. Patented Oct. 11, 1921.

Application filed November 12, 1920. Serial No. 423,590.

To all whom it may concern:

Be it known that I, MATTHEW J. CARBONI, citizen of the United States, and resident of New York, in the county of New York and 5 State of New York, have invented certain new and useful Improvements in Electric Signs, of which the following is a specification.

This invention relates generally to advertising devices and particularly to the kind known as illuminated signs.

The objects of my invention are to provide an inexpensive sign having readily exchangeable characters for the purpose of 15 varying the wording, and means whereby the expense of illuminating the sign is reduced to a minimum.

Another object of this invention is to provide in connection with such a sign two sets 20 of adjustable reflectors, one of which being adapted to reflect the light from the light source in a substantially vertical plane toward the sign characters; the other set adapted to reflect the light from top and 25 bottom toward said characters.

Another object of my invention is to provide in connection with such reflectors, means whereby the latter may be adjusted at 30 desired angles respective to the characters so as to utilize the light of the light source at maximum efficiency.

The foregoing and still further objects will be fully understood from the following description and the accompanying drawings forming part of this specification and in which:

Figure 1 is a front elevation of a sign showing the exchangeable characters.

Fig. 2 is a sectional view therethrough 40 taken on line 2—2 of Fig. 3.

Fig. 3 is a sectional view taken on line 3—3 of Fig. 1.

Fig. 4 is a sectional elevation taken on line 4—4 of Fig. 1.

Fig. 5 is a detail view showing the arrangement of a transverse member supporting a substantially vertically disposed reflector.

Fig. 6 is a detail perspective view of a 50 bottom reflector attached to its guide.

Referring to the drawings, numeral 1 represents the frame of a casing at the sides of which are provided supports or guides 2 for glidably engaging sign characters 3. These 55 characters may be slid from either side of

the casing. By changing these characters various words may be formed.

The character plates are preferably made of solid, non-transparent bases, from which are cut out the desired characters. The 60 cut out portion is preferably filled with a transparent substance as glass, porcelain or the like, indicated at 4. At the bottom of the casing, and disposed centrally between its sides, a longitudinal guide 5 is provided 65 wherein ride adjustable sockets 6 in which a light source 7 is mounted. At the top and bottom in near proximity to the characters, a set of longitudinal parallel guides 8 are provided wherein slide, by means of guide 70 bars 9, vertical or transverse connecting members 10. Adjustably mounted upon the latter are reflectors 11 provided at their center with a swivel joint 12 forming part of a tubular member 13, which may slide upon 75 vertical connecting member 10 and can be attached thereto at any position by means of thumb-screw 14. Due to the swivel joint connection, the reflectors, which are preferably cylindrically curved, may be set at any 80 desired angle respective to the characters 3. Reflectors 11 are substantially parallel with the long side of the characters. Parallel to guides 8 is a set of longitudinal connecting members 15, upon which are glidably mounted sleeves 13', provided with a set screw 14' 85 and a swivel joint 12' which support another set of cylindrically curved reflectors 11'. The latter are preferably disposed substantially parallel with the short side of the 90 characters 3 and may be set at any desired angle respective to the latter.

A preferred form of my sign is shown in the drawings where the light source is disposed centrally between two pairs of opposite disposed characters so that the light source is intermediate between at least two adjacent characters at each side of the sign. The vertical reflectors are preferably disposed near the extreme long sides of the two 100 adjacent characters so as to throw the light in a substantially vertical plane against the latter. The upper and lower reflectors 11' are inclined to concentrate the light against their respective characters from top and 105 bottom, and for this purpose they are somewhat inclined toward each other as shown in Fig. 2. In this manner a sign unit of two respectively four characters is created, lighted by one light source.

When the wording of the sign is to be changed, the characters are slid out from their guides 2 and replaced in desired succession, then the connecting members 10 are shifted to the extreme long sides of a group of two characters and the reflectors adjusted to reflect the light, each against one character, then the longitudinal reflectors 11' are shifted to proper position above and below the characters and inclined so as to reflect the light from top and bottom toward the respective upper and lower halves of the characters. In this manner the light is directed through the transparent part 4 of the characters thereby causing the latter to be visible at dark.

It is obvious that the drawings represent merely preferred forms of construction of my device, and that modifications or changes may be readily made within the broad scope of my invention. In view of the fact that signs are built for various requirements, I reserve for myself the right to make such changes as will be necessary to simplify their manufacture and modify their form and construction in accordance with such requirements.

Having thus described my invention, I claim:

1. A sign, comprising in combination, a casing, exchangeable, transparent characters arranged at both faces thereof, means for supporting said characters, a set of longitudinal parallel guides disposed in pairs at top and bottom and extending over the entire length of the casing, transverse connecting members glidably associated with said guides, cylindrically curved reflectors adjustably mounted upon said connecting members and adapted to be set at any desired angle respective to said characters, a set of longitudinal guide members disposed in pairs at top and bottom of said casing, a plurality of cylindrically curved reflectors adjustably mounted upon said members and adapted to be set at any desired angle respective to said characters, an adjustably mounted light source arranged at the bottom of said casing, said first mentioned reflectors being disposed in such a way as to reflect the light from said source in a substantially vertical plane toward said characters, the latter mentioned reflectors adapted to reflect light from the top and bottom toward said characters.

2. An illuminated sign, comprising in combination, a casing having open sides, exchangeable characters adapted to close said open sides, a light source disposed near the bottom of the casing intermediate between said characters, a set of longitudinal guides at top and bottom of said casing,

transverse connecting members adjustably mounted in said guides, cylindrically curved reflectors disposed substantially parallel with the long side of said characters, adjustably attached to said connecting members and adapted to be set at any desired angle respective to said characters, a set of longitudinal guide members disposed at top and bottom within the casing, a plurality of cylindrically curved reflectors slidably attached thereto and adapted to reflect light from top and bottom toward said characters, substantially as described.

3. An illuminated sign, comprising in combination, a casing, exchangeable characters at both sides thereof, an adjustable light source within the casing, a set of adjustable, substantially vertically disposed reflectors, a set of adjustable, substantially horizontally disposed reflectors, both sets of reflectors grouped within the casing and adapted to reflect light from the light source in a substantially vertical plane and from top and bottom, respectively, toward said characters.

4. In an illuminated sign, a casing, transparent characters at both sides thereof, an adjustable light source within the casing centrally disposed between two opposite pairs of said characters, adjustable reflectors provided at the outer length sides of each pair of characters, adjustable reflectors provided at top and bottom of each individual character, said reflectors adapted to reflect the light from the light source, respectively, in a substantially vertical plane, and from top and bottom toward said transparent characters.

5. An illuminated sign, comprising in combination, a casing, a slidably mounted adjustable light source, a group of transparent characters disposed at two sides thereof, a set of reflectors disposed at both longitudinal sides of each of said character groups, a set of other reflectors disposed at top and bottom of each individual character, both sets of reflectors adapted to reflect the light from the light source toward said characters.

6. In a sign, an exchangeable transparent character, an adjustable light source, a set of substantially longitudinally disposed reflectors, another set of substantially transversely disposed reflectors, said reflectors grouped and set around the character and adapted to reflect the light toward the characters, respectively, from both sides, the top and bottom.

Signed at New York in the county of New York and State of New York this 6th day of November A. D. 1920.

MATTHEW J. CARBONI.
